UNITED STATES PATENT OFFICE

ERNEST H. THOMPSON, OF EVANSTON, ILLINOIS

ALIGNING AND POSITIONING DEVICE FOR PISTON VALVES

Application filed December 3, 1928. Serial No. 323,542.

This invention relates to a novel device for accurately aligning and positioning a reciprocating piston valve member, particularly the form of piston valve used in the fluid meter construction as disclosed in applicant's copending application filed March 5, 1928, Serial No. 259,207, and in the improved type of meter as shown in other applications filed concurrently herewith.

10 In addition to properly and accurately positioning the piston valve member with respect to its valve ports, the present device also acts as an aligner for said valve member, to maintain the same in proper relation to its cylinder walls, said device being longitudinally disposed with respect to the cylinder and piston.

The piston valve in question is that type wherein said piston, being provided with 20 the necessary transverse passageways, is adapted to be reciprocated by the alternate energizing of oppositely disposed electromagnets or solenoids, the passageways in the piston valve being brought into and out 25 of registry with appropriate valve ports. It has developed in actual practice that there is not always a perfect registry between the valve passageways in the piston and the valve ports, nor do these parts always remain in accurate registering position, due 30 possibly to a slight rebound of the piston valve. It is absolutely essential, to the efficient and accurate working of the meter, that the ports do register correctly and that 35 they so remain in this relation up until the time the valve is shifted to its other or reverse position.

Applicant has heretofore used a spring 40 pressed cam faced detent, disposed transversely of the piston valve and adapted to snap into a recess in said piston valve at the proper time and hold the same in that position until pulled in the opposite direction in shifting the valve, a similar detent being provided near the opposite end of the piston to 45 hold the same in that position in a similar manner. In these devices, however, in performing the above described movements, the piston valve is given a lateral thrust upon disengaging itself from the cam faced detent

and owing to the delicate construction of this valve mechanism and the necessity for a very close fitting of the parts, this lateral thrust, although very slight, is sufficient to prevent an absolutely free movement of the piston 55 and an accurate working of the device as a whole.

The object of the present invention is to provide an arrangement, whereby the piston valve will be maintained in correct registering position with respect to the valve ports and at the same time the piston will be properly aligned; thus eliminating all tendency on the part of the piston to stick or bind in its supporting cylinder.

Briefly stated the present invention comprises a U-shaped spring clip secured in each end of the piston valve cylinder, and projecting inwardly in longitudinal alignment with the piston. The inner ends of these spring clips are curved first inwardly towards each other and then outwardly as shown in the drawings, the purpose of which will be apparent as the description progresses. Each end of the piston valve is provided with a longitudinal recess into which the U-shaped spring clips extend. Disposed transversely of the piston and across the said longitudinal recess, is a pin or the like, so positioned with respect to the inner end of the spring clip, that said pin will become engaged by and disengaged from said spring clip at the proper time, as the piston valve is reciprocated, during the operation of the device in connection with which this valve mechanism is used.

With this construction the main thrust is a longitudinal one and any tendency towards side thrust is equalized so that said spring clip device not only insures the correct positioning of the piston valve with respect to its valve ports, but also acts as an aligning device for said piston valve.

The preferred embodiment of the invention is illustrated in the accompanying drawings, in which

Fig. 1 is a view partly in elevation and partly in section illustrating the positioning and aligning device in operative position;

Fig. 2 is a sectional view on line 2—2; 100

Fig. 3 is an enlarged detail view of the various cooperating parts of the device; and Fig. 4 is a modification.

Referring to the drawings in detail, the 5 novel device is shown in combination with a piston valve construction used in connection with a fluid meter of the type wherein the liquid being measured is adapted to be admitted to and discharged from the meter in 10 certain timed relation. This admission and discharge is controlled by the periodical reciprocation of a valve piston 1, said piston being provided with annular passageways 2 and 3 adapted to register at the proper time 15 with ports 4 and 6, and 5 and 7 respectively.

The valve piston 1 is reciprocated by alternately energized electromagnets 8 and 9 encircling the opposite ends of the piston, said piston working or sliding within a sleeve or 20 cylinder 10, the opposite ends of said cylinder extending through and being secured to end plates 11 of the meter assembly.

The means for periodically energizing electromagnets and the particular relation between 25 the valve mechanism and the remaining parts of the meter, need no further description, as they form no part of the present invention, said invention relating merely to the means for positioning and aligning the 30 valve piston at the completion of each stroke of said piston.

The aligning device comprises an inwardly extending fork or U-shaped spring metal member 12, the base of said member being secured by a screw or the like 13 to a screw cap 14 threaded onto the outwardly extending end of the cylinder 10. In order to insure a liquid tight joint at this point, there is provided a washer or gasket 15 between the outer 35 edges of the cylinder 10 and the inner face of the cap 14. Interposed between the washer 15 and the base of the spring member 12 is a tubular spacer or the like 16. Slidable on this spacer 16 is a cup-shaped stop member or 40 buffer 17, to receive and cushion the impact of the valve piston as said piston reciprocates back and forth during the operation of the device.

The outer end of the valve piston 1 is provided with a cylindrical recess or chamber 18 into which the spring member 12 projects sufficiently to embrace a transverse pin 19 carried by the piston within the recess, said pin being so disposed as to intersect the longitudinal axis of said piston.

The free ends of the spring member 12 are curved first inwardly towards each other and then outwardly, to provide clamping fingers 20 for yieldingly permitting the passage therethrough of the pin 19 under the pull of the electromagnet, the spring pressure of these fingers 20 being sufficient however, to prevent a release of said pin should there be any tendency on the part of the piston to 25 move in a reverse direction upon the deener-

gizing of the electromagnet. It is, of course, to be understood that the location of the pin 19 with respect to the clamping fingers 20 is such as to maintain the passageways 2 and 3 of the piston 1 in proper and accurate register with their respective ports 4 and 6, and 5 and 7, as the case might be during the reciprocation of said valve piston. In addition to this function the spring member 12 will also maintain the piston in proper alignment with respect to its cylinder 10 as distinguished from the transversely arranged cam faced spring detent hereinbefore referred to.

All of the above detailed description has been directed to one end only of the valve piston, but it is of course to be understood that both ends of the piston may be similarly constructed and may be provided with a similar aligning and positioning device, said device functioning alternately as the valve piston reciprocates back and forth.

What I claim is:

1. A piston valve including a cylinder and cooperating ports, provided with means for maintaining said piston valve in proper registry with its ports, said means being concentrically disposed longitudinally of the piston and within the cylinder, but exteriorly of the valve chamber.

2. In a piston valve construction, the combination with a piston provided with passageways and a hollow end portion, of a cylinder provided with ports and means for positioning said piston so that the passageways thereof will be maintained in proper register with the ports in said cylinder, said means being concentrically disposed longitudinally of the piston and the cylinder and extending within the hollow-end portion of the piston.

3. In a piston valve construction, the combination with a piston provided with passageways and a hollow end portion, of a cylinder provided with ports, and resilient means carried within the end of the cylinder adapted to engage a portion of the piston within the hollow end of said piston for positioning and aligning said piston, said means being disposed longitudinally of the piston and cylinder.

4. In a piston valve construction, the combination with a piston provided with passageways, of a cylinder provided with ports, and means carried by the end of the cylinder adapted to engage an end portion of the piston for positioning and aligning said piston, said means comprising oppositely disposed spring fingers projecting inwardly and longitudinally of the piston, between which fingers said end portion is adapted to pass during the securing and releasing thereof.

5. In a piston valve construction, the combination with a piston provided with passageways, of a cylinder provided with ports, a head for said cylinder, a U-shaped re-

silient member secured to said head, a recess in the end of said piston to receive said resilient member, and means carried by the piston within said recess to be engaged and clamped by the open end of said U-shaped member, when the piston is moved to that end of the cylinder.

6. In a piston valve construction, the combination with a piston provided with passageways, of a cylinder provided with ports, a head for each end of said cylinder, a U-shaped resilient member secured to each head, a recess in the opposite ends of said piston to receive said resilient members, and means carried by the piston within each recess to be engaged and clamped by the open end of said U-shaped member as the piston reaches each of its extreme positions during the reciprocation thereof.

7. In a piston valve construction, the combination with a piston provided with passageways, of a cylinder provided with ports, a head for said cylinder, a U-shaped resilient member secured to said head, a recess in the end of said piston to receive said resilient member, and a transverse pin carried by the piston within said recess intersecting the axis of said piston, adapted to be engaged and clamped by the open end of said U-shaped member when the piston is moved to that end of the cylinder.

8. In a piston valve construction, the combination with a piston provided with passageways, of a cylinder provided with ports, a head for each end of said cylinder, a U-shaped resilient member secured to each head, a recess in the opposite ends of said piston to receive said resilient members, and a transverse pin carried by the piston within each recess intersecting the axis of said piston, adapted to be engaged and clamped by the open end of said U-shaped members for positioning the passageways of the piston with respect to their registering ports in said cylinder and to align said piston as the piston reaches its extreme positions during the reciprocation thereof.

9. The combination with a cylinder and piston and inlet and outlet passages for said cylinder, of a valve mechanism for controlling said passages, said mechanism comprising a piston provided with passageways and a hollow end portion, a cylinder provided with cooperating ports, and means carried by the end of the valve cylinder adapted to engage a portion of the valve piston within the hollow end portion of said piston for aligning said valve piston and maintaining the passageways in the valve piston in proper registry with the ports in the valve cylinder.

10. The combination with a cylinder and piston and inlet and outlet passages for said cylinder, of a valve mechanism for controlling said passages, said mechanism comprising a piston provided with passageways and a cyl-

inder provided with cooperating ports, and means carried by the end of the valve cylinder adapted to engage an end portion of the valve piston for positioning and aligning said valve piston, said means comprising oppositely disposed spring fingers projecting inwardly and longitudinally of the valve piston, between which fingers said end portion is adapted to pass during the securing and releasing thereof.

11. The combination with a cylinder and piston and inlet and outlet passages for said cylinder, of a valve mechanism for controlling said passages, said mechanism comprising a piston provided with passageways and a cylinder provided with cooperating ports, a head for the valve cylinder, a U-shaped resilient member secured to said head, a recess in the end of the valve piston to receive said resilient member, and means carried by the valve piston within said recess to be engaged and clamped by the open end of said U-shaped member when the valve piston is moved to that end of the cylinder.

12. The combination with a cylinder and piston and inlet and outlet passages for said cylinder, of a valve mechanism for controlling said passages, said mechanism comprising a piston provided with passageways and a cylinder provided with cooperating ports, a head for each end of said valve cylinder, a U-shaped resilient member secured to each head, a recess in the opposite ends of said valve piston to receive said resilient members, and means carried by the valve piston within each recess to be engaged and clamped by the open end of said U-shaped members as the valve piston reaches each of its extreme positions during the reciprocation thereof.

13. The combination with a cylinder and piston and inlet and outlet passages for said cylinder, of a valve mechanism for controlling said passages, said mechanism comprising a piston provided with passageways and a cylinder provided with cooperating ports, a head for the valve cylinder, a U-shaped resilient member secured to said head, a recess in the end of the valve piston to receive said resilient member, and a transverse pin carried by the valve piston within said recess intersecting the axis of said valve piston, adapted to be engaged and clamped by the open end of said U-shaped member when the valve piston is moved to that end of the cylinder.

14. The combination with a cylinder and piston and inlet and outlet passages for said cylinder, of a valve mechanism for controlling said passages, said mechanism comprising a piston provided with passageways and a cylinder provided with cooperating ports, a head for each end of said valve cylinder, a U-shaped resilient member secured to each head, a recess in the opposite ends of said valve piston to receive said resilient members,

and a transverse pin carried by the valve piston within each recess intersecting the axis of said valve piston, adapted to be engaged and clamped by the open end of said U-shaped member for positioning the passageways of the valve piston with respect to their registering ports in said valve cylinder and to align said valve piston as the said piston reaches its extreme positions during the reciprocation thereof.

10 15. In a piston valve construction, the combination with a piston provided with passageways, of a cylinder provided with ports in which said piston reciprocates, means in the end of the cylinder for cushioning the end thrust of said piston and means also carried by the end of the cylinder adapted to engage an end portion of the piston for positioning and aligning said piston, said last 20 mentioned means being disposed longitudinally of the piston and cylinder and independent of said first mentioned means.

16. In a piston valve construction, the combination with a piston provided with passageways, of a cylinder provided with ports in which said piston reciprocates, means in each end of the cylinder for cushioning the end thrusts of said piston and means also carried by each end of the cylinder adapted to 25 engage an end portion of the piston for positioning and aligning said piston, said last mentioned means being disposed longitudinally of the piston and cylinder and independent of said first mentioned means.

30 35. In testimony whereof I affix my signature.
